Patented Apr. 25, 1922.

Inventor

Alexander M. Bellony

UNITED STATES PATENT OFFICE.

ALEXANDER M. BELLONY, OF THE UNITED STATES ARMY.

CLAMPING MECHANISM.

1,414,250.

Specification of Letters Patent. Patented Apr. 25, 1922.

Original application filed April 26, 1919, Serial No. 293,031. Divided and this application filed April 26, 1919. Serial No. 293,028.

(FILED UNDER THE ACT OF MARCH 3, 1883, 22 STAT. L., 625.)

To all whom it may concern:

Be it known that I, ALEXANDER M. BELLONY, captain, Corps of Engineers, United States Army, a citizen of the United States, 5 stationed at Washington, District of Columbia, have invented an Improvement in Clamping Mechanism, of which the following is a specification.

The invention described herein may be 10 used by the Government, or any of its officers or employees in prosecution of work for the Government, or by any other person in the United States, without payment of any royalty thereon.

15 This invention relates to a novel clamping mechanism which, while designed more particularly for use in connection with pile-driving machines, is applicable for use in other situations; and the present application 20 covering this invention is a divisional application of a parent application filed April 26, 1919, Serial No. 293,031.

The object of the invention is to provide a 25 novel clamping mechanism which is extremely simple in construction, very easy to operate, thoroughly efficient in operation, and durable in use.

With this object in view, and others appearing as the specification proceeds and the 30 nature of the invention more fully develops, the invention resides in a type of clamping mechanism controllable from the top of a pile-driving machine, or other object in connection with which it is used.

35 The invention is graphically illustrated in the accompanying drawing, in which like reference characters designate corresponding parts throughout the several views. The views comprising the drawings may be briefly 40 described as follows.

Figure 1 is a view in side elevation of my clamping mechanism, showing the application of the clamping mechanism to a portion of the pile-driving machine, shown partly 45 in section;

Figure 2 is a view in front elevation thereof.

50 1 designates a clamping dog, the jaw 2 of which is adapted to engage an object to be clamped, and the head 3 of which is pivotally supported upon a pivot 4 projecting transversely through the legs of a U-shaped clamp support 5 carried by a clamping screw

6, which is swiveled in the base of said U-shaped clamp-support 5, and is threaded 55 through the base of a U-shaped bracket 7, the legs of which are provided with flanged terminals 8, 8, adapted to be secured to a stationary support A, as by means of the rivets 9, 9. This support may be a channel-iron, as shown, forming part of the movable upper frame of a pile-driving machine (such as shown in my said co-pending application) and carrying wheels (one thereof, a, being shown in the drawing) moving on a track 60 C, forming part of the stationary lower frame of a pile-driving machine. The legs of the U-shaped bracket 7 are provided with longitudinally extending recesses 10, 10, in their inner faces, which recesses extend from 65 a point in line with the flanged terminals 8, 8, upward toward the bridge or base portion of the U-shaped bracket 7. The ends of the pivot pin 4 project into said recesses, as 70 shown. The groove and pin construction 75 just described permits vertical movement of the support 5 relative to the bracket 7 and prevents relative rotation thereof. A handle or crank 11 is secured to the clamp screw 6. A hook 12 is carried by the bracket 7, preferably on the bridge or base portion thereof, and the chain 13, or the like, is secured to the clamping dog 1, whereby, when the latter is swung from the operative to the inoperative position thereof, it may be supported 80 in the latter position by hooking the chain 13 on the hook 12.

In operation, assuming that the clamping dog 1 is in inoperative position, that is, in a position oblique to and away from the 90 track channel A or like object, all that is necessary to be done is to swing the clamping dog downward until its jaw 2 is beneath the track channel A, and then rotate the crank 11 to cause a vertical upward 95 movement of the clamp support 5, the pin 4 and the clamping dog 1. Such upward vertical movement is continued until the clamp is securely tightened.

The clamping mechanism described has 100 been designed for particular use in pile-driving machines, which embody a movable upper frame and a lower stationary frame, which upper frame it is advantageous to clamp to the lower frame after the former 105 has been moved relative to the latter; but,

of course, the clamping mechanism is obviously applicable to other situations and is susceptible of general use.

Having thus fully described my invention, what I claim as new and desire to secure by Letters Patent is:—

1. The combination with a transportable structure and a rail for supporting said structure, of a U-shaped clamp bracket carried by the structure, a clamping dog, a U-shaped clamp support to which said clamping dog is pivotally secured, and screw means carried by said clamp bracket for raising and lowering said clamp support, said bracket being provided with means cooperating with the pivot pin of the clamping dog for preventing rotary movement of said clamp support relative to said clamp bracket.
2. The combination with a transportable structure and a rail for supporting said structure, of a clamp bracket carried by the structure and provided with longitudinally extending recesses, a clamp support, a clamping dog pivoted to said support, the pivot pin of the clamping dog projecting into said recesses to prevent rotary movement of said clamp support relative to said bracket, and means carried by said clamp bracket for raising and lowering said clamp support.
3. The combination with a transportable structure and a rail for supporting the structure, of a clamp bracket carried by the

structure, a clamp support slidable in the bracket, a clamping dog pivoted to the support and having an end to contact under the flange of the rail and a connection between the bracket and support whereby the support may be moved to bring the end of the dog into contact with the rail or release it therefrom.

4. The combination with a transportable structure and a rail for supporting said structure; of a bracket mounted on said structure, a clamping dog, a frame slidably mounted in the bracket and pivotally supporting said dog, means carried by the bracket and connected with the frame to actuate the latter, and additional means in connection with the bracket and cooperating with the pivotal pin of the dog to prevent rotary movement of the frame during its actuation.

5. The combination with a transportable structure and a rail for supporting said structure; of a bracket mounted on said structure, a clamping dog, a frame mounted for vertical movement within the bracket and pivotally supporting said dog, a screw carried by the bracket and connected with the frame to actuate the latter, and additional means in connection with the bracket and cooperating with the pivotal pin of the dog to prevent rotary movement of the frame when vertically actuated.

ALEXANDER M. BELLONY.
